SPECIFIC SUBSTITUTED IMINOPYRROLIDINES
Newman M. Bortnick, Oreland, and Marian F. Fegley
Philadelphia, Pa., assignors to Rohm & Haas Company,
Philadelphia, Pa., a corporation of Delaware
No Drawing. Filed May 15, 1961, Ser. No. 109,844
19 Claims. (Cl. 260—313)

This invention deals with specific substituted iminopyrrolidines as new compositions of matter. It also deals with a method for the preparation of these specific substituted iminopyrrolidines.

The compounds of this invention may be represented by the formula

(A)

The symbol R^1 represents hydrocarbon groups of 1 to 10 carbon atoms, preferably alkyl, aralkyl, cycloalkyl, aryl and alkaryl. The symbol R^2 represents a hydrogen atom or an alkyl group of 1 to 4 carbon atoms. The symbols R^3 and R^4 may be a hydrogen atom or hydrocarbon groups containing from 1 to 10 carbon atoms, including alkyl, aralkyl, cycloalkyl, aryl and alkaryl groups. In addition, R^1 and R^2 taken together with the carbon atoms to which they are joined may form a carbocyclic ring containing 5 to 6 carbon atoms which in turn may have alkyl substituents containing a total of no more than 4 additional carbon atoms. In addition, R^2 and R^3 taken together with the carbon atoms to which they are joined may form a carbocyclic ring containing 5 to 6 carbon atoms which in turn may have alkyl substituents containing a total of no more than four additional carbon atoms. In addition, R^3 and R^4 taken together with the carbon atoms to which they are joined may form a carbocyclic ring containing 5 to 6 carbon atoms which in turn may have alkyl substituents containing a total of no more than 4 additional carbon atoms. The total number of carbon atoms in the cyano-ketone should not exceed 24. The preferred embodiments are those in which R^1 and R^4 are alkyl groups, R^2 is a hydrogen atom, and R^3 is a methyl group. R^1 , R^3 , and R^4 may typically individually represent methyl, butyl, octyl, benzyl, phenylbutyl, cyclopentyl, cyclohexyl, phenyl, naphthyl, butylphenyl groups, and the like.

Each of the symbols R and R⁵ represents a hydrogen atom, an alkyl group of 1 to 18 carbon atoms, an alkenyl group of 3 to 18 carbon atoms, an aryl group of up to 10 carbon atoms, an aralkyl group of up to 18 carbon atoms, an alkarylalkyl group of up to 30 carbon atoms, an alkoxyalkyl group of 3 to 24 carbon atoms, a hydroxyalkyl group of 2 to 12 carbon atoms, and an alkylaminoalkyl group of 3 to 18 carbon atoms provided that the amino group is a secondary or tertiary structure, that is non-primary. Alkyl, in the above definition, is to be construed to include cycloalkyl and alkylcycloalkyl within the range of carbon atoms previously set forth. It is preferred that R and R⁵ represent the same groups within any single product.

Typical R and R⁵ representations are hydrogen, methyl, ethyl, butyl, octyl, decyl, dodecyl, octadecyl, cyclopentyl, cyclohexyl, butylcyclohexyl, octylcyclohexyl, butylcyclohexylethyl, propenyl, butenyl, hexenyl, octenyl, decenyl, dodecenyl, octadecenyl, phenyl, naphthyl, benzyl, phenylethyl, phenylbutyl, phenyldodecyl, methylphenyl, ethylphenyl, butylphenyl, octylphenyl, nonylphenyl, decylphenyl, hexadecylphenyl, octadecylphenyl, methylbenzyl, ethylbenzyl, butylbenzyl, octylbenzyl, dodecyl-

2

benzyl, butylphenylbutyl, octylphenylethyl, dioctylphenylethyl, dodecylphenyloctyl, methoxyethyl, methoxypropyl, methoxyhexyl, methoxydecyl, methoxyoctadecyl, ethoxyethyl, ethoxybutyl, ethoxyoctyl, ethoxydodecyl, propoxyethyl, propoxybutyl, propoxyheptyl, propoxytetradecyl, butoxyethyl, butoxybutyl, butoxyoctyl, butoxydodecyl, butoxyoctadecyl, pentoxyethyl, pentoxybutyl, pentoxydecyl, hexoxyethyl, hexoxyhexyl, hexoxydodecyl, hexoxyoctadecyl, heptoxyethyl, heptoxyoctyl, octoxyethyl, octoxybutyl, octoxyoctyl, octoxydodecyl, nonoxypropyl, nonoxyheptyl, nonoxytridecyl, decoxyethyl, decoxyoctyl, undecoxybutyl, dodecoxypropyl, dodecoxydecyl, dodecoxydodecyl, tridecoxyethyl, tetradecoxypropyl, pentadecoxypentyl, hexadecoxybutyl, heptadecoxyethyl, octadecoxyethyl, octadecoxyhexyl, hydroxyethyl, hydroxypropyl, hydroxybutyl, hydroxypentyl, hydroxyoctyl, hydroxydecyl, hydroxydodecyl, ethylaminoethyl, propylaminoethyl, butylaminopropyl, octylaminoethyl, hexylaminoethyl, heptylaminopentyl, octylaminoethyl, nonylaminoethyl, ethylaminononyl, decylaminopropyl, propylaminododecyl, dodecylaminooethyl, dodecylaminoethyl, dodecylaminohexyl, N-methyl-N-ethylaminoethyl, N-propyl-N-ethylaminoethyl, N-butyl-N-pentylaminoethyl, N-octyl-N-hexylaminobutyl, and N-decyl-N-butylaminobutyl.

The symbol X represents a cyano group, an amino-methyl group, an $R^6\text{NH}$ group, or an $R^7\text{A}$ group, in which R^6 represents a hydrogen atom, an alkyl group of 1 to 18 carbon atoms, an alkenyl group of 3 to 18 carbon atoms, an aralkyl group of up to 18 carbon atoms, an alkarylalkyl group of up to 30 carbon atoms, an alkoxy-alkyl group of 3 to 24 carbon atoms, a hydroxyalkyl group of 2 to 12 carbon atoms, and an alkylaminoalkyl group of 3 to 18 carbon atoms provided that the amino group is a secondary or tertiary structure, that is non-primary. Alkyl, in the above definition, is to be construed to include cycloalkyl and alkylcycloalkyl within the range of carbon atoms previously set forth.

Typical R⁶ representations are hydrogen, methyl, ethyl, butyl, octyl, decyl, dodecyl, octadecyl, cyclopentyl, cyclohexyl, butylcyclohexyl, octylcyclohexyl, butylcyclohexyl-ethyl propenyl, butenyl, hexenyl, octenyl, decenyl, dodecenyl, octadecenyl, benzyl, phenylethyl, phenylbutyl, phenyldodecyl, methylbenzyl, ethylbenzyl, butylbenzyl, octylbenzyl, dodecylbenzyl, butylphenylbutyl, octylphenylethyl, dioctylphenylethyl, dodecylphenyloctyl, methoxyethyl, methoxypropyl, methoxyhexyl, methoxydecyl, methoxyoctadecyl, ethoxyethyl, ethoxybutyl, ethoxyoctyl, ethoxydodecyl, propoxyethyl, propoxybutyl, propoxyheptyl, propoxytetradecyl, butoxyethyl, butoxybutyl, butoxyoctyl, butoxydodecyl, butoxyoctadecyl, pentoxyethyl, pentoxybutyl, pentoxydecyl, hexoxyethyl, hexoxyhexyl, hexoxydodecyl, hexoxyoctadecyl, heptoxyethyl, heptoxyoctyl, octoxyethyl, octoxybutyl, octoxyoctyl, octoxydodecyl, nonoxypropyl, nonoxyheptyl, nonoxytridecyl, decoxyethyl, decoxyoctyl, undecoxybutyl, decoxypropyl, dodecoxydodecyl, tri-decoxyethyl, tetradecoxypyropyl, pentadecoxypentyl, hexadecoxypybutyl, heptadecoxethyl, octadecoxethyl, octadecoxypyhexyl, hydroxyethyl, hydroxypropyl, hydroxybutyl, hydroxypentyl, hydroxyoctyl, hydroxydecyl, hydroxydodecyl, ethylaminoethyl, propylaminoethyl, butylaminoethyl, octylaminoethyl, hexylaminoethyl, heptylaminoethyl, octylaminoethyl, nonylaminoethyl, ethylaminononyl, decylaminopropyl, propylaminododecyl, decylaminooethyl, dodecylaminobutyl, dodecylaminohexyl, N-methyl-N-ethylaminoethyl, N-propyl-N-ethylaminoethyl, N-butyl-N-pentylaminoethyl, N-octyl-N-hexylaminobutyl, and N-decyl-N-butylaminobutyl.

The symbol R^7 represents a hydrogen atom, an alkyl group of 1 to 12 carbon atoms, an alkenyl group of 3

to 12 carbon atoms, an aryl group of up to 10 carbon atoms, an aralkyl group of up to 12 carbon atoms, an alkarylalkyl group of up to 12 carbon atoms, an alkoxyalkyl group of 3 to 12 carbon atoms, a hydroxyalkyl group of up to 12 carbon atoms, an alkylaminoalkyl group of 3 to 18 carbon atoms, provided that the amino group is a secondary or tertiary structure, that is non-primary. Alkyl, in the above definition is to be construed to include cycloalkyl and alkylcycloalkyl within the range of carbon atoms previously set forth.

The symbol A represents a chalcogen having an atomic weight of 16 to 32, that is, oxygen or sulfur.

The compounds of the present invention are made by reacting the compound having the formula

(B)

with a compound having the formula HX in which X has the significance previously set forth except for the aminomethyl representation. X as aminomethyl is made, from the corresponding compound wherein X equals the cyano group, by hydrogenation.

It is also possible to obtain the compounds of the present invention wherein R^1 is alkyl by employing the tautomer of B having the formula

(C)

in place of the aforementioned iminopyrrolidine reactant. R^8 is hydrogen or alkyl of 1 to 9 carbon atoms.

With respect to the aforementioned iminopyrrolidine reactant, when R^5 equals hydrogen, the compound represented by the formula B is to varying degrees, according principally to reaction conditions and the values of R, R^1 , R^2 , R^3 , and R^4 , in tautomeric relationship with the compounds having the following structures:

(D)

and

(E)

It is highly probable, based on the best experimental and analytical evidence, that the predominant tautomeric product is that of Formula E, but appreciable amounts of B and D are undoubtedly present.

In the present sense, Formula B will be referred to as the principal form of the possible tautomeric structures (B, C, D, and E), but such a reference is meant to include all of the tautomeric forms. Formulas B and C represent the predominant tautomeric forms when R^5 is alkyl.

Typical reactants having the formulas B or C include

- 5-laurylimino-2-methyl-1-pyrroline,
- 2-methyl-5-laurylimino-2-pyrroline,
- 1-lauryl-2-imino-5-methylenepyrrolidine,
- 2,4-dihexyl-5-laurylimino-4-methyl-2-pyrroline,
- 2,4-dihexyl-5-laurylimino-4-methyl-1-pyrroline,
- 3-hexyl-2-imino-1-lauryl-3-methyl-5-hexylideneepyrrolidine,
- 4-methyl-2,4-diphenyl-5-laurylimino-2-pyrroline,

- 2-laurylimino-3,3-pentamethylene-2,3,4,5,6,7-hexahydroindole
- 2,4,4-trimethyl-5-octadecylimino-2-pyrroline,
- 3,3-dimethyl-2-imino-1-octadecyl-5-methylenepyrrolidine,
- 2,3-dimethyl-5-octadecylimino-2-pyrroline,
- 2,3-dimethyl-5-octadecylimino-1-pyrroline,
- 1-octadecyl-2-imino-4-methyl-5-methylenepyrrolidine,
- 4-methyl-2,4-dicyclohexyl-5-octadecylimino-2-pyrroline,
- 3-cyclohexyl-2-imino-3-methyl-1-octadecyl-5-cyclohexylidenepyrrolidine,
- 5-octadecylimino-4-methyl-2,4-dicyclohexyl-1-pyrroline,
- 2-octadecylimino-3,3,6-trimethyl-2,3,4,5,6,7-hexahydroindole,
- 2-imino-1-octadecyl-3,3,6-trimethyl-2,3,4,5,6,7-hexahydrodroindole,
- 2,4,4-trimethyl-5-methylimino-2-pyrroline,
- 1-ethyl-2-imino-3,3-dimethyl-5-methylenepyrrolidine,
- 2,4,4-trimethyl-5-butylimino-2-pyrroline,
- 1-butyl-2-imino-3,3-dimethyl-5-methylenepyrrolidine,
- 2,4,4-trimethyl-5-benzylimino-2-pyrroline,
- 1-benzyl-2-imino-3,3-dimethyl-5-methylenepyrrolidine,
- 2,4,4-trimethyl-5-(3-methoxypropylimino)-2-pyrroline,
- 1-(3-methoxypropyl)-2-imino-3,3-dimethyl-5-methylenepyrrolidine,
- 2,4-dimethyl-4-neopentyl-5-(3-diethylaminopropylimino)-2-pyrroline,
- 1-(3-diethylaminopropyl)-2-imino-3-methyl-3-neopentyl-5-methylenepyrrolidine,
- 4-methyl-4-ethyl-2-propyl-5-(2-methyl-2-hydroxypropylimino)-2-pyrroline,
- 1-(2-methyl-2-hydroxypropyl)-2-imino-3-methyl-3-ethyl-5-methylenepyrrolidine,
- 2,4,4-trimethyl-5-phenylimino-2-pyrroline,
- 1-phenyl-2-imino-3,3-dimethyl-5-methylenepyrrolidine,
- 2,4,4-trimethyl-5-p-tolylimino-2-pyrroline,
- 2-p-tolylimino-3,3-dimethyl-5-methylenepyrrolidine,
- 2- α -naphthylimino-3,3-pentamethylene-2,3,4,5,6,7-hexahydroindole,
- 2,4,4-trimethyl-2-hydroxy-5-benzyliminopyrrolidine,
- 2-hydroxy-2,4,4-trimethyl-5-methylinopyrrolidine,
- 2-allylimino-3,3-pentamethylene-7a-hydroxy-2,3,3a,4,5,6,7,7a-octahydroindole,
- 2-(2-ethoxyethylimino)-7a-hydroxy-3,3,6-trimethyl-2,3,3a,4,5,6,7,7a-octahydroindole,
- 1-benzyl-5-benzylimino-2,4,4-trimethyl-2-pyrroline,
- 1-benzyl-2-benzylimino-3,3-dimethyl-5-methylenepyrrolidine,
- 1-benzyl-5-benzylimino-2,3-dimethyl-2-pyrroline,
- 1-benzyl-2-benzylimino-4-methyl-5-methylenepyrrolidine,
- 1-benzyl-5-benzylimino-2,4-dihexyl-4-methyl-2-pyrroline,
- 1-benzyl-2-benzylimino-3-hexyl-3-methyl-5-hexylidene-pyrrolidine,
- 1-benzyl-5-benzylimino-2,4-bis(2-methylpropyl)-4-methyl-2-pyrroline,
- 1-benzyl-2-benzylimino-3-methyl-3-(2-methylpropyl)-5-(2-methylpropylidene)pyrrolidine,
- 1-benzyl-5-benzylimino-2,4-dimethyl-4-(2,2-dimethylpropyl)-2-pyrroline,
- 1-benzyl-2-benzylimino-3-methyl-3-(2,2-dimethylpropyl)-5-methylenepyrrolidine,
- 1-butyl-5-butylimino-2,4,4-trimethyl-2-pyrroline,
- 1-butyl-2-butylimino-3,3-dimethyl-5-methylenepyrrolidine,
- 1-butyl-5-butylimino-2-butyl-3-methyl-1,4,5,6,7,7a-hexahydroisoindole,
- spiro{3,3-dimethylbicyclo(2.2.1)heptane-2,4'[1'-butyl-2'-methyl-5'-butylimino-2'-pyrroline]},
- 1-butyl-2-butylimino-3,3,6-trimethyl-2,3,4,5,6,7-hexahydroindole,
- 1-dodecyl-5-dodecylimino-2,4,4-trimethyl-2-pyrroline,
- 1-dodecyl-2-dodecylimino-3,3-dimethyl-5-methylenepyrrolidine,
- 1-p-tolyl-2-p-tolylimino-3,3-pentamethylene-2,3,4,5,6,7-hexahydroindole,

1-(2-butoxyethyl)-2-(2-butoxyethylimino)-3,3-penta-methylene-2,3,4,5,6,7-hexahydroindole,
 1-(3-dimethylaminopropyl)-2-(3-dimethylaminopropyl-imino)-3,3-pentamethylene-2,3,4,5,6,7-hexahydro-indole,
 1-hexadecyl-5-hexadecylimino-2,4-dimethyl-4-(2,2-di-methylpropyl)-2-pyrrolidine,
 1-hexadecyl-2-hexadecylimino-3-methyl-3-(2,2-dimethyl-propyl)-5-methylenepyrrolidine,
 1-(2-ethylaminoethyl)-5-(2-ethylaminoethylimino)-2,4-dimethyl-4-(2,2-dimethylpropyl)-2-pyrrolidine,
 1-(2-ethylaminoethyl)-2-(2-ethylaminoethylimino)-3-methyl-3-(2,2-dimethylpropyl)-5-methylenepyrrolidine,
 1-(2-phenylethyl)-5-(2-phenylethylimino)-2,4-dimethyl-4-(2,2-dimethylpropyl)-2-pyrrolidine,
 1-(2-phenylethyl)-2-(phenylethylimino)-3-methyl-3-(2,2-dimethylpropyl)-5-methylenepyrrolidine, and
 1-dodecyl-2-imino-3,3-dimethyl-5-methylenepyrrolidine.

Typical reactants having the formula HX include hydrocyanic acid, water, methanol, ethanol, propanol, 2-methylpropanol, 2,2-dimethylpropanol, 1-butanol, 2-ethylhexanol, 1-octanol, 1-dodecanol, 1-octadecanol, benzyl alcohol, β -phenylethanol, 3-dimethylamino-1-propanol, 2-dibutylaminoethanol, 3-butylaminopropanol, 2-methoxyethanol, 2-butoxyethanol, 2-methoxy-1-propanol, cyclohexanol, furfuryl alcohol, tetrahydrofurfuryl alcohol, tetrahydrobenzyl alcohol, 2-norcamphanylmethanol, 2-norcamphenylmethanol, 2-phenoxyethanol, 2-methylmercaptoethanol, 2-butylmercaptoethanol, 2-vinoxyethanol, 2-vinylmercaptoethanol, allyl alcohol, crotyl alcohol, α -naphthylmethanol, β -naphthylmethanol, hydrogen sulfide methyl mercaptan, butyl mercaptan, cyclohexyl mercaptan, phenyl mercaptan, benzyl mercaptan, 2-methoxyethyl mercaptan, 2-ethoxyethyl mercaptan, 2-butoxyethyl mercaptan, 2-phenoxyethyl mercaptan, dodecyl mercaptan, hexadecyl mercaptan, octadecyl mercaptan, 2-methoxypropyl mercaptan, 2-butoxypropyl mercaptan, 2-butoxybutyl mercaptan, 2-butoxycyclohexyl mercaptan, β -phenylethyl mercaptan, γ -phenylbutyl mercaptan, benzylmercaptoethyl mercaptan, phenylmercaptoethyl mercaptan, methyl thioglycolate, ethyl thioglycolate, butyl thioglycolate, octyl thioglycolate, octadecyl thioglycolate, methyl β -mercaptopropionate, β -mercaptopropionitrile, ethylene glycol, diethylene glycol, propylene glycol, trimethylene glycol, tetramethylene glycol, 2-ethyl-1,3-hexanediol, ethanedithiol, 1,2-propanedithiol, 1,3-propanedithiol, 1,2-butanedithiol, 1,3-butanedithiol, 1,4-butanedithiol, butenediol, butyndiol, ammonia, methylamine, butenylamine, benzylamine, ethylbenzylamine, dodecyl-phenylpropylamine, ethoxybutylamine, ethanolamine, and 3-dimethylaminopropylamine.

It should be noted that in the HX reactant when X stands for R^6NH , the nitrogen atom must be attached to a hydrogen atom or to a carbon atom that is in turn attached to no more than two other carbon atoms. Similarly, it should be noted when X stands for R^7A . Otherwise, the present reaction is sterically hindered and not readily consummated.

When X represents R^7A , it is preferred to employ the R^7AH reactant in excess of the amount required, in order to assure completeness of reaction and maximum yields. The reaction temperature ranges from normal room temperature (about 20° C.) to about 75° C., preferably about 20° to 60° C. The reaction is readily conducted without the use of a solvent but if such is desired, there may be employed an inert volatile organic solvent, such as benzene, toluene, xylene, heptane, hexane, methylene chloride, chloroform, and the like. The products formed are either crystalline solids or viscous liquids. The products do not require any purification, although selective extraction or recrystallization from a solvent such as octane may be employed if a product of high purity is desired.

When X represents R^6NH , it is preferable to employ the R^6NH_2 reactant in excess of the amount required in order to assure completeness of reaction and maximum yields. The reaction temperature ranges from about 0° to somewhat below 75° C., such as 70° C., preferably about 20° to 60° C. The reaction may be conducted in the presence of an inert volatile organic solvent, such as benzene, toluene, xylene, heptane, hexane, methylene chloride, chloroform, and the like. The product formed is frequently crystalline in nature and may be separated by filtration and purified by recrystallization from a suitable solvent, such as the hydrocarbon solvents, as desired.

The course and completeness of the reaction is readily followed by use of the infrared absorption spectra and it has been repeatedly observed that infrared bands characteristic of the reactants disappear as the reaction reaches completion. This is frequently a valuable aid in determining the rate and extent of the present reaction as will be apparent to one skilled in the art.

While the present reaction is consummated by a mere mixing of the selected reactants, it is frequently advantageous to add from 0.1 to 10.0 mole percent of an acid in order to expedite the reaction. This acid may be employed as the acid salt of the amine reactant and such is the preferred way. The common laboratory acids are satisfactory, economical and, therefore, preferred in this respect. Suitable for this use are hydrochloric, hydrobromic, sulfuric, and the like, preferably in the form of the salt of the amine reactant.

It is possible, if desired, in some instances such as with ammonia and methylamine to prepare the present compounds by reacting a ketonitrile having the formula

with the amine reactants previously discussed in a molecular ratio of substantially one of the former to two of the latter.

The present compounds are prepared by reacting an equivalent of the defined heterocyclic reactant with substantially an equivalent of hydrocyanic acid. The present reaction is conducted at atmospheric pressures and at a temperature range of 0° to 150° C., preferably, at 20° to 100° C., or at superatmospheric pressures at temperatures as high as 325° C. It is necessary to conduct the reaction in a basic medium and since the heterocyclic reactants are already basic in nature, no catalyst is required. However, occasionally it may be advantageous to add small portions of acid, conveniently mineral acids, such as hydrochloric acid, in order to expedite the reaction. However, the amount of acid to be added should always be such that the basic medium is maintained.

While no catalyst is actually required, as stated heretofore, it may be advantageous in some instances to supply a cyanide ion generating catalyst in which case the catalyst is employed preferably in amounts of about 0.1 to 20% by weight of the total weight of the reactants. Suitable as a catalyst are alkali metals and their carbonates, the lower alkoxides, oxides, hydroxides, peroxides, and cyanides of the alkali metals and alkaline earth metals, tertiary amines, and quaternary ammonium bases. Actually there may be employed as catalyst any base whose aqueous 0.1 molar solution has a pH of about at least 9. Typical examples of the catalyst that may be used are sodium, potassium, lithium, sodium methoxide, potassium butoxide, lithium ethoxide, magnesium ethoxide, sodium oxide, potassium hydroxide, calcium oxide, barium hydroxide, strontium hydroxide, sodium peroxide, magnesium peroxide, potassium cyanide, lithium cyanide, barium cyanide, magnesium cyanide, sodium carbonate, potassium carbonate, trimethylamine, triethylamine, triethanolamine, octyldimethylamine, N-methylmorpholine, benzyltrimethylammonium hydroxide, dibenzylidemethylammo-

nium hydroxide, dodecenytriethylammonium hydroxide, and the like. The alkali metal cyanides are particularly effective for the instant purposes.

It is advantageous to introduce the hydrocyanic acid at such a rate that reaction occurs promptly and the rate of introduction may be regulated so as to substantially equal the rate of reaction as will be clear to one skilled in the art. Under such circumstances, no adverse side reactions are noticed and high yields are obtained frequently approaching 100 percent. Hydrocyanic acid may be introduced into the reaction mixture in either the gaseous or liquid state as is desired and substantially similar results are obtained in either case. The rate of addition of hydrocyanic acid varies with the temperatures at which the reactions are carried out. When high temperatures are employed, reaction times may be shortened from hours to minutes, particularly when high molecular weight pyrroline starting materials are employed.

If desired, a volatile inert organic solvent may be employed in order to obtain maximum reaction benefits. The solvent may be of the hydrocarbon type, such as hexane, heptane, benzene, toluene, and the like, or it may be selected from the class of secondary and tertiary alcohols, ethers, substituted amides, nitriles, and halogenated hydrocarbons, as desired. At the conclusion of the reaction, the product may be isolated by neutralization of any catalyst which had been added, separation from the salts so formed and removal of volatile solvents and the starting materials. Further purification may be accomplished by selective extraction, distillation, or crystallization, whichever is appropriate, as is conventional for any one skilled in the art.

The products in which X represents an aminomethyl group are prepared by hydrogenation from the corresponding products where X is a cyano group.

The hydrogenation is carried out in the presence of a catalyst. Suitable as catalysts are Raney nickel, Raney cobalt, cobalt with ammonia, nickel with ammonia, cobalt-copper, nickel-cobalt, palladium, platinum, ruthenium, and the like. The catalyst may be employed in any convenient particle size. Generally, the smaller particle sizes produce the higher rates. If desired, the catalyst may be deposited on a carrier material in order to extend and activate it. Suitable for use as a carrier are activated alumina, activated clays, silica gel, charcoal, asbestos, pumice, and the like. Room temperatures and somewhat above may be employed when a noble metal is used as the catalyst. When the other materials are employed as catalyst, temperatures in the range of about 75° to 250° C. are employed with about 100° to 200° C. preferred. It is preferred that the hydrogenation be carried out at the lowest temperature at which reduction can occur within the ranges previously set out. An inert, volatile, organic solvent may be desirable, such as hydrocarbons, alcohols, ethers, and the like. The lower alkanols, such as methanol or ethanol, are particularly suited for this use. When the noble metals are used as catalysts, a small amount of an activating acid, such as acetic or hydrochloric, may be employed.

Pressures in the range of atmospheric to 10,000 p.s.i.g. are employed. Actually, higher pressures may be used if desired but in most instances, no apparent advantages are achieved for the extra effort extended. The reaction shown proceeds a little more rapidly at the higher pressures but lower pressures may be successfully employed with some of the catalysts, especially Raney nickel. The preferred range of pressures is atmospheric to 100 p.s.i.g. when noble metal catalysts are employed and 250 to 5000 p.s.i.g. when the transition metal catalysts are used.

The present reaction should be concluded as soon as one mole of hydrogen has reacted. Otherwise, if the reaction is conducted for periods of time that are substantially longer than that required for one mole of hydrogen to react, there is some chance that hydrogenolysis of the ring may occur. In some instances, this has been observed

when the reaction was conducted for prolonged periods of time. While no specific time limit in minutes or hours can be given, since actual times will vary with iminopyrrolidine reactants, catalysts, temperatures, and pressures, it is emphasized that the reaction should be concluded after substantially one mole of hydrogen has reacted.

A preferred way of consummating the present reaction is to introduce the iminopyrrolidine reactant along with a catalyst of the type described heretofore into a pressure retention reaction vessel and add hydrogen until a certain desired pressure is reached. The reaction vessel or at least the reaction ingredients may be preferably agitated such as by shaking or rotating until a precalculated drop in pressure is observed. This significant drop in pressure indicates that an equivalent amount of hydrogen has reacted. This precalculated pressure drop, indicating that an equivalent amount of hydrogen has reacted, is readily calculable by known methods. Therefore, an indication of reaction completion may be readily calculated and observed.

At the conclusion of the reaction, the product is obtained by filtering off the catalyst and stripping off the solvent. If desired, the products may be purified by distillation or recrystallization from hydrocarbons, ethers, or the like.

The compounds of this invention have been presented in their free-base form and in this free-base form, they possess the valuable characteristics and concurrent utilities previously referred to. However, it is to be construed that the present invention includes the acid addition salts of these free-base products also. It is desirable, in some instances, to employ the present products in their water-soluble salt form. For instance, in pesticidal applications, it is highly desirable to deal with water-soluble compounds in order that satisfactory spray solutions may be formulated. In other applications, wherein any physiological benefits are desired, it is frequently advantageous to employ the present products in their organic salt form in order to provide substantial neutrality with stability.

In order to prepare the salt forms of the present compounds, it is necessary only to react these compounds with a stoichiometric amount of the selected acid. The salt formation occurs readily at room temperature without the aid of a catalyst. If solid reactants are employed, it may be advantageous to use an inert volatile solvent such as benzene, toluene, xylene, hexane, heptane, methylene chloride, chloroform, or the like. The solvent can then be readily removed at the conclusion of the reaction by conventional methods. The salt product does not require any further purification although recrystallization from a solvent such as isoctane may be resorted to if a product of high purity is demanded.

While it is believed clear to one skilled in the art from the above description how the salts are prepared, such salt formation may be specifically illustrated by indicating that one would take an equivalent amount of a selected compound of this invention in its free-base form and then add a stoichiometric amount of a selected acid which would, for instance, be 36.5 parts of hydrochloric acid, 98 parts of sulfuric acid, 60 parts of acetic acid, 72 parts of acrylic acid, and the like. The corresponding hydrochloric, sulfuric, acetic and acrylic acid salts respectively are readily formed. Similarly, other salt products may be prepared.

The products of the present invention are useful as fungicides, particularly when applied against *Monilina fructicola* and *Stemphylium sarcinaeforme*. Complete inhibition is frequently observed in concentrations of about 0.1% and lower and many of the compounds are effective in concentrations as low as 0.01% and lower when applied and evaluated according to standard procedures and techniques.

This application is a continuation-in-part of United States patent applications Serial Nos. 718,506 and 718,510,

filed March 3, 1958, and 742,726 and 742,753, filed June 18, 1958, all of which are now abandoned.

The compounds of this invention, as well as the methods for their preparation, may be more fully understood from the following examples which are offered by way of illustration and not by way of limitation. Parts by weight are used throughout.

Example 1

Hydrogen cyanide (4 parts) is added dropwise to 1-butyl-5-butylimino-2,4,4-trimethyl-2-pyrrolidine (24 parts). An exothermic reaction occurs. The mixture is then stirred for one hour and the excess hydrogen cyanide is then removed by stripping under reduced pressure. The product has a boiling point of 114° to 115° C. (0.9 mm.), an n_D^{25} value of 1.4710, and is obtained in a 70% yield (17.5 parts). The product contains 16.01% nitrogen (theoretical 15.95%), 73.12% carbon (theoretical 72.94%), 11.16% hydrogen (theoretical 11.10%). The infrared spectrum confirms the structure of the product as 2-cyano-1-butyl-5-butylimino-2,4,4-trimethylpyrrolidine.

The same product is obtained by reacting hydrocyanic acid with 1-butyl-2-butylimino-3,3-dimethyl-5-methylenepyrrolidine.

In similar fashion are prepared 2-cyano-1-dodecyl-5-dodecylimino-2,4,4-trimethylpyrrolidine from 1-dodecyl-5-dodecylimino-2,4,4-trimethyl-2-pyrrolidine, 1-benzyl-5-benzylimino-2-cyano-4-methyl-2,4-bis(2-methylpropyl)pyrrolidine from 1-benzyl-5-benzylimino-4-methyl-2,4-bis-(2-methylpropyl)-2-pyrrolidine, 2-cyano-1-hexyl-5-hexylimino-2,4-bis-(2-methylpropyl)-4-methylpyrrolidine from 1-hexyl-5-hexylimino-2,4-bis-(2-methylpropyl)-4-methyl-2-pyrrolidine, 1-butylimino-2-butyl-3-cyano-3-methyl-1,3,3a,4,5,6,7,7a-octahydroisoindole from 1-butylimino-2-butyl-3-methyl-1,4,5,6,7,7a-hexahydroisoindole, and 1-(2-butoxyethyl)-2-(2-butoxyethylimino)-7a-cyano-3,3-pentamethylene-2,3,3a-4,5,6,7,7a-octahydroindole from 1-(2-butoxyethyl)-2-(2-butoxyethylimino)-3,3-pentamethylene-2,3,4,5,6,7-hexahydroindole.

Example 2

To a solution of 1-(2-hydroxyethyl)-5-(2-hydroxyethylimino)-2,4,4-trimethyl-2-pyrrolidine (53 parts) dissolved in acetonitrile (50 parts) is added hydrogen cyanide (9 parts) in a dropwise manner. The reaction mixture is maintained at 70° to 82° C. for two hours. Excess hydrogen cyanide and the acetonitrile solvent are removed by stripping under reduced pressure. The residue crystallizes on cooling and recrystallized from ether to give the product, 2-cyano-1-(2-hydroxyethyl)-5-(2-hydroxyethylimino)-2,4,4-trimethylpyrrolidine, having a melting point of 87° to 89° C. Recrystallization from benzene gives the analytical sample having a melting point of 91.5° to 92° C. The product contains 17.6% nitrogen (theoretical 17.6%), 60.4% carbon (theoretical 60.2%), and 8.9% hydrogen (theoretical 8.8%). The yield of recrystallized product is 60% of the theoretical. Examination of the spectrum in the infrared range supports the stated structure.

The same product is obtained by reacting hydrocyanic acid with 1-(2-hydroxyethyl)-2-(2-hydroxyethylimino)-3,3-dimethyl-5-methylenepyrrolidine.

In a similar fashion are prepared 1-butyl-5-butylimino-2-cyano-2,4,4-triethylpyrrolidine from 1-butyl-5-butylimino-2,4,4-triethyl-2-pyrrolidine, 7a-cyano-1-(3-dimethylaminopropyl)-2-(3-dimethylaminopropylimino)-3,3-pentamethylene-2,3,3a,4,5,6,7,7a-octahydroindole from 1-(3-dimethylaminopropyl)-2-(3-dimethylaminopropylimino)-3,3-pentamethylene-2,3,4,5,6,7-hexahydroindole, and 2-cyano-1-(2-ethylaminoethyl)-5-(2-ethylaminoethylimino)-2,4-dimethyl-4-(2,2-dimethylpropyl)-pyrrolidine from 2,4-dimethyl-4-(2,2-dimethylpropyl)-1-(2-ethylaminoethyl)-5-(2-ethylaminoethylimino)-2-pyrrolidine.

Example 3

Hydrogen cyanide (2 parts) is added to 3,3-dimethyl-2-imino-1-lauryl-5-methylenepyrrolidine (12 parts) (n_D^{25} 75

1.4782—the liquid isomer). The reaction mixture is stirred for thirty minutes after the addition is complete and the mild exotherm has subsided. Unreacted hydrogen cyanide is removed by stripping under reduced pressure. The product contains 11.68% nitrogen (theoretical 13.15%), 67.24% carbon (theoretical 75.18%), and 11.96% hydrogen (theoretical 11.67%). This analysis indicates that the reaction has proceeded to convert 60% of the iminopyrrolidine to the cyanopyrrolidine. Distillation of a portion of the stripped material shows that the product can be distilled but that separation of the starting material from the final product is not easily carried out by simple distillation. The product has a boiling point of 164° to 172° C. (0.8 mm.) and has an n_D^{25} value of 1.4738. The sample contains 12.02% nitrogen. This corresponds to a mixture of 68% of the cyanoimino-pyrrolidine and 32% of the starting iminopyrrolidine.

The same product is obtained by reacting hydrocyanic acid with 5-imino-1-lauryl-2,4,4-trimethyl-2-pyrrolidine.

In a similar fashion, 5-benzylimino-2-cyano-2,4,4-trimethylpyrrolidine is prepared from 5-benzylimino-2,4,4-trimethyl-2-pyrrolidine. In this case, too, the reaction does not go to completion and separation from the starting material is difficult. The product has a boiling point of 145° to 166° C. (1.4 mm.), and an $n_D^{25.5}$ value of 1.5447. The product contains 15.7% nitrogen (theoretical 17.4%) and has a neutral equivalent of 237 (theoretical 241). The infrared absorption spectra in both of these instances confirms the conclusion that in each instance the reaction has not been forced to go to completion and absorption bands corresponding to both the starting material and the final product are easily recognized.

Example 4

A much purer product is obtained from the addition of hydrogen cyanide to 5-cyclohexylimino-2,4,4-trimethyl-2-pyrrolidine. In this instance, hydrogen cyanide (4 parts) is added dropwise to 5-cyclohexylimino-2,4,4-trimethyl-2-pyrrolidine (30 parts). The reaction mixture is allowed to stand overnight at room temperature. The reaction mixture is then distilled to give the product, having a boiling point of 117° to 127° C. (0.2 mm.) (16 parts) which solidifies in the receiver. The product contains 17.4% nitrogen (theoretical 18.0%). Only small amounts of the starting 5-cyclohexylimino-2,4,4-trimethyl-2-pyrrolidine are present in the product and are recognized by inspection of the infrared absorption spectrum of the product.

The same product is obtained by reacting hydrocyanic acid with 2-cyclohexylimino-3,3-dimethyl-5-methylenepyrrolidine.

In a similar fashion, 2-cyano-5-octadecylimino-2,4,4-trimethylpyrrolidine is prepared from 5-octadecylimino-2,4,4-trimethyl-2-pyrrolidine, 5-butylimino-2-cyano-2,4,4-trimethylpyrrolidine is prepared from 5-butylimino-2,4,4-trimethyl-2-pyrrolidine, 1-butylimino-3-cyano-3-methyl-1,3,3a,4,5,6,7,7a-octahydroisoindole is prepared from 1-butylimino-3-methyl-1,4,5,6,7,7a-hexahydroisoindole, and 7a-cyano-2-(3-dimethylaminopropylimino)-3,3-pentamethylene-2,3,3a,4,4,5,6,7,7a-octahydroindole is prepared from 2-(3-dimethylaminopropylimino)-3,3-pentamethylene-2,3,4,5,6,7-hexahydroindole.

Example 5

Hydrogen cyanide (3 parts) is added to a slurry of 5-laurylimino-2,4,4-trimethyl-1-pyrrolidine (15 parts) (the solid isomer) in dimethyl formamide (150 parts). Pyridine hydrochloride (0.1 part) is added when the reaction appears to be sluggish. The mixture becomes homogeneous one-half hour after the addition of the catalyst. Examination of the spectrum of the reaction mixture in the infrared range 24 hours after the materials are combined shows that 2-cyano-5-laurylimino-2,4,4-trimethylpyrrolidine has formed.

Example 6

1-butyl-5-butylimino-2-cyano-2,4,4-trimethylpyrrolidine

(12 parts) and Raney nickel (1 part) are heated at 150°-160° C. in a hydrogen atmosphere at 1750 p.s.i.g. for 1.5 hours in a rocking autoclave. The bomb is cooled and vented and the reaction mixture is filtered to separate it from the catalyst. The filtrate is distilled under reduced pressure to give the product, 2-aminomethyl-1-butyl-5-butylimino-2,4,4-trimethylpyrrolidine, having a boiling point of 123°-128° C. (2.0 mm.) and an n_D^{25} value of 1.4784. The product contains 71.70% carbon (71.85% theoretical), 12.48% hydrogen (12.44% theoretical), 15.3% nitrogen (15.7% theoretical), and has a neutral equivalent of 144.5 (134 theoretical).

In like manner, there are prepared 2-aminomethyl-1-hexyl-5-hexylimino-2,4-bis-(2-methylpropyl)-4-methylpyrrolidine from 2-cyano-1-hexyl-5-hexylimino-2,4-bis-(2-methylpropyl)-4-methylpyrrolidine, 2-aminomethyl-5-butylimino-2,4,4-trimethylpyrrolidine from 2-cyano-5-butylimino-2,4,4-trimethylpyrrolidine, and 2-aminomethyl-5-dodecylimino-2,4-dimethyl-4-(2,2-dimethylpropyl)pyrrolidine from 2-cyano-2,4-dimethyl-4-(2,2-dimethylpropyl)pyrrolidine. Similarly, there are prepared 7a-aminomethyl-2-butylimino-3,3,6-trimethyl-2,3,3a,4,5,6,7,7a-octahydroindole from 2-butylimino-7a-cyano-3,3,6-trimethyl-2,3,3a,4,5,6,7,7a-octahydroindole, spiro{3,3-dimethylbicyclo-(2.2.1)-heptane-2,4'-[2'-aminomethyl-1'-butyl-5'-butylimino-2'-methylpyrrolidine]} from spiro{3,3-dimethylbicyclo-(2.2.1)-heptane-2,4'-[1'-butyl-5'-butylimino-2'-cyano-2'-methylpyrrolidine]}, and 3-aminomethyl-2-butylimino-3-methyl-1,3,3a,4,5,6,7,7a-octahydroisoindole from 2-butylimino-3-cyano-3-methyl-1,3,3a,4,5,6,7,7a-octahydroisoindole.

Example 7

Hydrogen cyanide (3 parts) is added to a slurry of 5-laurylimino-2,4,4-trimethyl-1-pyrrolidine (15 parts) (the solid isomer) in dimethyl formamide (150 parts). Pyridine hydrochloride (0.1 part) is added when the reaction appears to be sluggish. The mixture becomes homogeneous one-half hour after the addition of the catalyst. Examination of the spectrum of the reaction mixture in the infrared range 24 hours after the materials are combined shows that 2-cyano-5-laurylimino-2,4,4-trimethylpyrrolidine has formed.

This reaction mixture and Raney nickel (10 parts) are heated at 135° to 140° C. in a hydrogen atmosphere at 1700 p.s.i.g. for 1.5 hours in a rocking autoclave. The bomb is cooled and vented and the reaction mixture is filtered to separate it from the catalyst. The dimethyl formamide is removed by stripping at reduced pressure. The product, which solidifies on standing, is identified as 2-aminomethyl-5-laurylimino-2,4,4-trimethylpyrrolidine by means of its infrared spectrum.

Example 8

Benzylamine hydrochloride (0.2 part), 5-benzylimino-2,4,4-trimethyl-2-pyrrolidine (43 parts), and benzylamine (21.5 parts) are mixed and allowed to stand for four days at room temperature. The infrared absorption spectrum of the mixture establishes the absence of significant amounts of either of the starting materials. The bands at 1683 cm.⁻¹, 1608 cm.⁻¹ and 1582 cm.⁻¹ which are characteristic of the benzyliminotrimethylpyrrolidine are missing from the spectrum. There is a single band at 3220 cm.⁻¹ in the NH stretching region. If unreacted benzylamine were present, there would be two bands in the 3300-3500 cm.⁻¹ region. A strong band appears at 1627-1640 cm.⁻¹. This band is characteristic of 5-alkylimino-2,4,4-trimethylpyrrolidines which carry substituents in the 2-position. The product is identified as 2-benzylamino-5-benzylimino-2,4,4-trimethylpyrrolidine.

The same compound is prepared by reacting benzylamine with 2-benzylimino-3,3-dimethyl-5-methylenepyrrolidine.

In a similar fashion, dodecylamine, 2-methoxypropylamine, 2-hydroxyethylamine and 3-dimethylaminopropylamine are added to 5-butylimino-2,4,4-trimethyl-2-pyr-

roline in the presence of one mole percent of their hydrochlorides as catalysts to give

5-dodecylamino-5-butylimino-2,4,4-trimethylpyrrolidine, 2-(2-methoxypropylamino)-5-butylimino-2,4,4-trimethylpyrrolidine, 2-(2-hydroxyethylamino)-5-butylimino-2,4,4-trimethylpyrrolidine, and 2-(3-dimethylaminopropylamino)-5-butylimino-2,4,4-trimethylpyrrolidine, respectively.

Similarly, 2-ethylhexylamine, cyclohexylamine, and allylamine are added to 5-cyclohexylimino-2,4-dimethyl-4-(2,2-dimethylpropyl)-2-pyrrolidine in the absence of a catalyst to give

2-(ethylhexylamino)-5-cyclohexylimino-2,4-dimethyl-4-(2,2-dimethylpropyl)pyrrolidine, 2-cyclohexylamino-5-cyclohexylimino-2,4-dimethyl-4-(2,2-dimethylpropyl)pyrrolidine, and 2-allylamino-5-cyclohexylimino-2,4-dimethyl-4-(2,2-dimethylpropyl)pyrrolidine.

Likewise, 3,3,6-trimethyl-2,3,4,5,6,7-hexahydro-2-(3-methoxypropylimino)indole is reacted with ethylamine to give 2-(3-methoxypropylimino)-3,3,6-trimethyl-7a-ethylamino-2,3,3a,4,5,6,7,7a-octahydroindole.

Example 9

When either methylamine or ammonia is employed, it is convenient to charge an excess of either of these together with the selected iminopyrrolidine to a pressure vessel and allow the reaction mixture to stand for several days. The vessel is warmed to 50° or 60° C. in order to hasten the process. The vessel is then cooled and vented to the atmosphere and the product is isolated. In this fashion, methylamine is reacted with

1-methyl-3-methylimino-3,3a,4,5,6,7-hexahydroisoindole, 2-methylimino-3,3-pentamethylene-2,3,4,5,6,7-hexahydroindole, and 5-octadecylimino-2,4,4-trimethyl-2-pyrrolidine

to give, respectively,

1-methylamino-1-methyl-3-methylimino-1,3,3a,4,5,6,7,7a-octahydroisoindole, 3,3-pentamethylene-2-methylimino-7a-methylamino-2,3,3a,4,5,6,7,7a-octahydroindole, and 2-methylamino-2,4,4-trimethyl-5-octadecylimino-pyrrolidine.

Similarly, ammonia and

5-laurylimino-2,4-dimethyl-4-(2,2-dimethylpropyl)-2-pyrrolidine, 2,4-bis(2-methylpropyl)-4-methyl-5-methylimino-2-pyrrolidine, and 2,4-diphenyl-4-methyl-5-methylimino-2-pyrrolidine

give, respectively,

2-amino-2,4-dimethyl-4-(2,2-dimethylpropyl)-5-lauryliminopyrrolidine, 2-amino-2,4-bis(2-methylpropyl)-4-methyl-5-methyliminopyrrolidine, and 2-amino-2,4-diphenyl-4-methyl-5-methyliminopyrrolidine.

Example 10

In the case of both methylamine and ammonia, it has been found possible to prepare the compounds of this invention directly from ketonitriles. Thus, 2,2-dimethyl-4-oxopentanone (63 parts), and methylamine (74 parts) are combined in a Dry-Ice cooled pressure reactor. The reactor is sealed and allowed to warm to room temperature. After standing three days at room temperature, the reactor is vented and the bomb contents are stripped at reduced pressure and room temperature to remove any low boiling materials. The residue is leached with cold diethyl ether and the solid product is recrystallized from diethyl ether to give 2-methylamino-5-methylimino-2,4,4-trimethylpyrrolidine (38 parts).

The product has a melting point of 58°-60° C. and a neutral equivalent of 89.1 (84.5 theoretical). A second crop of crystals (6.4 parts) is separated from the mother liquors after most of the diethyl ether has evaporated. The total yield of recrystallized product is 41% based on ketonitrile starting material. From the filtrate is recovered a 35% yield of 5-methylimino-2,4,4-trimethyl-2-pyrrolidine having a boiling point of 90°-100° C. at 10 mm. absolute pressure and a neutral equivalent of 128.4 (138 theoretical).

Both reaction products on catalytic hydrogenation over Raney nickel in methanol solution gave 5-methylimino-2,4,4-trimethylpyrrolidine in yields of approximately 90% (melting point 108°-111.5° C.).

In a similar fashion, 1-(2-oxocyclohexyl)-cyclohexane-carbonitrile and 2-methyl-2-hexyl-4-oxodecanonitrile and ammonia give 7a-aminoo-2-imino-3,3-pentamethylene-2,3,3a,4,5,6,7,7a-octahydroindole and 2,4-dihexyl-4-methyl-5-imino-2-aminopyrrolidine, respectively. Likewise, methylamine and 2-acetylcyclohexane-carbonitrile give 1-methyl-1-methylamino-3-methylimino-1,3,3a,4,5,6,7,7a-octahydroisoindole, and spiro [3,3-dimethylbicyclo-(2.2.1)heptane-2,4'-(2'-methyl-2'-methylamino-5'-methyliminopyrrolidine)] is obtained by the reaction of methylamine and 3,3-dimethyl-2-(2-oxopropyl)-bicyclo-(2.2.1)heptane-2-carbonitrile.

Example 11

Butyl mercaptan (18 parts) is added dropwise with stirring to 5-benzylimino-2,4,4-trimethyl-2-pyrrolidine (46 parts) which contains sodium methoxide (0.2 parts) as catalyst. The temperature of the reaction mixture rises from 25° to 35° C. during the course of this addition. The reaction mixture is warmed in an oil bath until the last traces of solid dissolves at 70° C. The oil bath is removed and stirring is continued for several hours. The infrared absorption spectrum of the product shows a strong band at 1615-1620 cm.⁻¹. The presence of this band and the absence of bands 1683 cm.⁻¹, 1608 cm.⁻¹, and 1582 cm.⁻¹, characteristic of the starting 2-pyrrolidine reactant, and the absence of bands in the 2500-2600 cm.⁻¹, the S-H stretching region, show that the resulting liquid product is 5-benzylimino-2-butylthio-2,4,4-trimethylpyrrolidine.

The same compound is prepared by reacting butyl mercaptan with 2-benzylimino-3,3-dimethyl-5-methylenepyrrolidine.

In the same manner, 5-benzylimino-2,4,4-trimethyl-2-pyrrolidine reacts with methyl mercaptan, phenyl mercaptan, cyclohexyl mercaptan, dodecyl mercaptan, and octadecyl mercaptan to give

2-methylthio-5-benzylimino-2,4,4-trimethylpyrrolidine, 2-benzylthio-5-benzylimino-2,4,4-trimethylpyrrolidine, 2-cyclohexylthio-5-benzylimino-2,4,4-trimethylpyrrolidine, 2-dodecylthio-5-benzylimino-2,4,4-trimethylpyrrolidine, and 2-octadecylthio-5-benzylimino-2,4,4-trimethylpyrrolidine, respectively.

When gaseous hydrogen sulfide is bubbled into 5-benzylimino-2,4,4-trimethyl-2-pyrrolidine and the reaction mixture is allowed to stand overnight in the presence of 2 mole percent of sodium hydrosulfide catalyst, the corresponding 2-mercapto-5-benzylimino-2,4,4-trimethylpyrrolidine is obtained.

In a similar fashion, 5-methylimino-2,4,4-trimethyl-2-pyrrolidine and ethyl thioglycolate give 2-ethoxycarbonylmethylthio-5-methylimino-2,4,4-trimethylpyrrolidine; 2-butoxyethylmercaptan and 5-phenylimino-2,4-diphenyl-4-methyl-2-pyrrolidine give 2-(2-butoxyethylthio)-5-phenylimino-2,4-diphenyl-4-methylpyrrolidine; 2-cyclohexylimino-3,3-pentamethylene-2,3,4,5,6,7-hexahydroindole and thiophenol give

7a-phenylthio-2-cyclohexylimino-3,3-pentamethylene-2,3,3a,4,5,6,7,7a-octahydroindole; and 1-dodecylimino-3-methyl-1,4,5,6,7,7a-hexahydroisoindole and benzylmercaptan give 1-dodecylimino-3-methyl-3-benzylthio-1,3,3a,4,5,6,7,7a-octahydroisoindole.

Example 12

A. Water (10 parts) and 5-benzylimino-2,4-trimethyl-2-pyrrolidine (46 parts) are combined and allowed to stand at room temperature in a stoppered flask. The flask is shaken occasionally to keep the reaction mixture emulsified. After six days, benzene (40 parts) is added and the mixture is heated at 40° C. until all the solid dissolves. The aqueous layer is separated and discarded. A white solid separates when heptane is added to the benzene solution. The solid, after recrystallization from benzene and heptane, is found to melt at 117° to 121° C.

B. The same product is obtained as follows: 2,2-dimethyl-4-oxopentanone (31.2 parts) and benzylamine (26.8 parts) are combined and allowed to stand in a stoppered flask at room temperature. Within one month the material becomes milky and solid begins to separate. After six months it solidifies. The solid is recrystallized from acetone to give the product (36 parts), 2-hydroxy-5-benzylimino-2,4,4-trimethylpyrrolidine, having a melting point of 119.5° to 123° C.

The product has a molecular weight of 243 (232 theoretical), a hydroxyl number of 250 (241 theoretical) and contains 72.6% carbon (72.4% theoretical), 9.0% hydrogen (8.7% theoretical), and 11.9% nitrogen (12.1% theoretical). The spectrum of this solid in the infrared range shows weak absorption at 3440 cm.⁻¹, and a strong band at 1618 cm.⁻¹ which shows the presence of the 5-benzyliminopyrrolidine structure. Hydrogenation of a sample of this material over Raney nickel gives 2-benzylimino-3,3,5-trimethylpyrrolidine, having a melting point of 71° to 73° C. Mixed melting points show that the product obtained by the above described methods A and B are identical.

Example 13

The procedure of Example 12A is repeated, except that benzene and a drop of hydrochloric acid are added initially and the mixture is heated at 40° to 50° C. until solution is complete. The product, 2-hydroxy-2,4,4-trimethyl-5-benzyliminopyrrolidine, is obtained in 85% yield on dilution of the benzene solution with heptane. In like manner, 5-dodecylimino-2,4,4-trimethyl-2-pyrrolidine is converted to 2-hydroxy-5-dodecylimino-2,4,4-trimethylpyrrolidine and 5-octadecylimino-2,4-dimethyl-4-(2,2-dimethylpropyl)-2-pyrrolidine gives 2-hydroxy-5-octadecylimino-2,4-dimethyl-4-(2,2-dimethylpropyl)pyrrolidine.

Example 14

When the 5-imino-2-pyrrolines have even slight solubility in water, the hydration may be accomplished by simply mixing the iminopyrrolines with water and stirring and warming until hydration is complete. This hydration reaction can be followed by noting the change in the ultraviolet absorption spectrum of the aqueous solution. The iminopyrrolines of this invention show an absorption band at 235-245 mm. When hydration occurs, this band disappears and in its place a band at 205 mm. is observed. The magnitude of the extinction coefficients may be plotted as a function of time to determine the rate of the reaction. Varying conditions of time and temperature and pH of the aqueous solution have been studied. When the pH of the medium is adjusted to 7 or below, the mixture becomes homogeneous owing to salt formation; the salts are much more soluble in water than are the free bases. Thus, at pH 7, 5-laurylimino-2,4,4-trimethyl-2-pyrrolidine is observed to hydrate to the corresponding 2-hydroxy-5-laurylimino-2,4,4-trimethylpyrrolidine to the extent of 50% after 18 hours at room temperature (the molar extinction coefficient

dropped from 4750 to 2350 during this period); after 90 hours, the band at 238 mm. had completely disappeared. Hydration is accomplished at 50° C. and at 80° C. in very much shorter times. In the latter instance, the reaction is complete in less than 8 hours.

By operating at pH 7 at room temperature, it is possible to hydrate many of the iminopyrrolines used as starting materials in this invention. Under these conditions little or no opening of the iminopyrrolidine ring occurs. On prolonged heating in aqueous acid solution, however, it is possible to further hydrolyze 2-hydroxy-5-alkylimino-2,4,4-trimethylpyrrolidines to 2,2-dimethyl-4-oxopentanoic acid and the alkyl amine (as its salt). This side reaction is suppressed by operation at low temperatures. In this manner are prepared 2-hydroxy-5-phenylimino-2,4,4-trimethylpyrrolidine, 2-hydroxy-2,3-dimethyl-5-cyclohexyliminopyrrolidine, 7a-hydroxy-2-(2-ethoxyethylimino)-3,3-pentamethylene-2,3,3a,4,5,6,7,7a-octahydroindole, 3-hydroxy-1-laurylimino-3-methyl-1,3,3a,4,5,6,7,7a-octahydroisoindole, 2-hydroxy-5-octadecylimino-4-methyl-2,4-(2-methylpropyl)pyrrolidine, and 7a-hydroxy-2-norcamphanylmethylimino-3,3-dimethyl-2,3,3a,4,5,6,7,7a-octahydroindole from the corresponding iminopyrrolidines.

Example 15

Alcohols react in much the same fashion as does water. These additions occur in the presence of either acidic or alkaline catalysts or in the absence of any added catalyst. The iminopyrroline starting materials are sufficiently basic to serve as their own alkaline catalysts. The reaction may be carried out by mixing stoichiometric quantities of the two reactants in the absence of a solvent or in the presence of an inert diluent or, one of the two reagents, preferably the alcohol, may be added in large excess. The latter technique is especially applicable when the lower alkanols are employed, especially if the reaction products are to be isolated as their salts. Again, as is the case when the addition of water to the iminopyrrolidines is examined, the ultraviolet absorption spectrum of the reaction mixture may be employed to establish whether or not addition has occurred and to what extent the reaction has proceeded at any time. Following the procedure of Example 14, but substituting the alcohols for the water employed, adding a mole of fumaric acid and a mole of the corresponding iminopyrrolidine to the alkanol, warming to achieve homogeneity, and allowing to stand at room temperature overnight gives: 2-methoxy-5-methylimino-2,4,4-trimethylpyrrolidine, 2-ethoxy-5-benzylimino-2,4,4-trimethylpyrrolidine, 2-(2-ethylhexoxy)-2,3-dimethyl-5-lauryliminopyrrolidine, 2-butoxy-5-phenylimino-2,4,4-trimethylpyrrolidine, 7a-methoxy-2-cyclohexylimino-3,3-dimethyl-2,3,3a,4,5,6,7,7a-octahydroindole, 2-allyloxy-5-(2-phenoxyethylimino)-2,4,4-trimethylpyrrolidine, and 2-methoxy-5-benzylimino-4-methyl-2,4-bis(2-methylpropyl)-pyrrolidine as their acid fumarate salts. When hydrogen chloride is substituted for fumaric acid, the corresponding hydrochloride salts result and when methanesulfonic acid is substituted for fumaric acid, the corresponding methanesulfonates result. Omission of the acid or use of minor amounts of acids as catalysts give the corresponding free bases. These products may frequently be applied as solutions in the alkanols in which they are prepared.

Example 16

When high molecular weight alcohols are used, it is sufficient to mix stoichiometric equivalents of the two reagents and warm and test the ultraviolet absorption spectrum from time to time until the reaction is shown to be complete by disappearance of the characteristic iminopyrroline peak. In this manner are prepared 2-dodecoxy-5-laurylimino-2,4,4-trimethylpyrrolidine, 2-hexadecoxy-5-octadecylimino-2-methylpyrrolidine and

2-benzyloxy-5-benzylimino-2,4-dimethyl-4-(2,2-dimethylpropyl)pyrrolidine. Again, acid catalysis markedly accelerates this process.

The compounds of this invention have been presented in their free-base form and in this free-base form, they possess the valuable characteristics and concurrent utilities previously referred to. However, it is to be construed that the present invention includes the salts of these free-base products also. It is desirable, in some instances, to employ the present products in their water-soluble salt form. For instance, in many pesticidal applications, it is highly desirable to deal with water-soluble compounds in order that satisfactory spray solutions may be formulated. In other instances, it is frequently advantageous to employ the present products in their organic salt form in order to provide substantial neutrality with stability.

We claim:

1. The compound, a member selected from the class consisting of the compound having the formula

and the acid addition salts thereof, in which R and R^5 are each members selected from the class consisting of hydrogen, alkyl groups of 1 to 18 carbon atoms, phenyl, naphthyl, phenylalkyl groups of up to 18 carbon atoms, alkylphenylalkyl groups of up to 30 carbon atoms, alkoxyalkyl groups of 3 to 24 carbon atoms, hydroxylalkyl groups of 2 to 12 carbon atoms, and alkylaminoalkyl groups of 3 to 18 carbon atoms, R^1 taken individually represents a member selected from the class consisting of alkyl, phenylalkyl, cycloalkyl, phenyl, naphthyl, and alkylphenyl groups of no more than 10 carbon atoms, R^2 taken individually represents a member selected from the class consisting of hydrogen and alkyl groups of 1 to 4 carbon atoms, R^3 and R^4 taken individually represent members selected from the class consisting of hydrogen, alkyl, cycloalkyl, phenylalkyl, phenyl, naphthyl and alkylphenyl groups of up to 10 carbon atoms, R^1 and R^2 taken collectively with the carbon atoms to which they are joined form a carbocyclic ring of 5 to 6 carbon atoms free of aromatic unsaturation including alkyl substituents of a total of no more than 4 additional carbon atoms, R^2 and R^3 taken collectively with the carbon atoms to which they are joined form a carbocyclic ring of 5 to 6 carbon atoms free of aromatic unsaturation including alkyl substituents of a total of no more than 4 additional carbon atoms, R^3 and R^4 taken collectively with the carbon atoms to which they are joined form a carbocyclic ring of 5 to 6 carbon atoms free of aromatic unsaturation including alkyl substituents of a total of no more than 4 additional carbon atoms, and X is a member selected from the class consisting of cyano, aminoethyl, and R^6NH group, and an R^7A group, in which R^6 is a member selected from the class consisting of a hydrogen atom, an alkyl group of 1 to 18 carbon atoms, an alkenyl group of 3 to 18 carbon atoms, a phenylalkyl group of up to 18 carbon atoms, an alkylphenylalkyl group of up to 30 carbon atoms, an alkoxyalkyl group of 3 to 24 carbon atoms, a hydroxylalkyl group of 2 to 12 carbon atoms, an alkylaminoalkyl group of 3 to 18 carbon atoms, R^7 is a member selected from the class consisting of a hydrogen atom, an alkyl group of 1 to 12 carbon atoms, an alkenyl group of 3 to 12 carbon atoms, phenyl, naphthyl, a phenylalkyl group of up to 12 carbon atoms, an alkylphenylalkyl group of up to 12 carbon atoms, an alkoxyalkyl group of 3 to 12 carbon atoms, a hydroxylalkyl group of up to 12 carbon atoms, and an alkylaminoalkyl group of 3 to 18 carbon atoms, and A is a halogen of an atomic weight of 16 to 32.

2. The compound having the formula

in which R and R⁵ are alkyl groups of 1 to 18 carbon atoms, R¹, R³, and R⁴ are alkyl groups of 1 to 10 carbon atoms, and R² is a hydrogen atom.

3. The compound having the formula

in which R and R⁵ are alkyl groups of 1 to 18 carbon atoms, R¹, R³, and R⁴ are alkyl groups of 1 to 10 carbon atoms, and R² is a hydrogen atom.

4. The compound having the formula

in which R and R⁵ are alkyl groups of 1 to 18 carbon atoms, R¹, R³, and R⁴ are alkyl groups of 1 to 10 carbon atoms, and R² and R⁶ represent hydrogen atoms.

5. The compound having the formula

in which R and R⁵ are alkyl groups of 1 to 18 carbon atoms, R¹, R³, and R⁴ are alkyl groups of 1 to 10 carbon atoms, R² is a hydrogen atom, and R⁶ represents an alkyl group of 1 to 18 carbon atoms.

6. The compound having the formula

in which R and R⁵ are alkyl groups of 1 to 18 carbon atoms, R¹, R³, and R⁴ are alkyl groups of 1 to 10 carbon atoms, R² and R⁷ represent hydrogen atoms, and A represents a chalcogen of an atomic weight of 16 to 32.

7. The compound having the formula

in which R and R⁵ are alkyl groups of 1 to 18 carbon atoms, R¹, R³, and R⁴ are alkyl groups of 1 to 10 carbon atoms, R² is a hydrogen atom, R⁷ is an alkyl group of 1 to 12 carbon atoms, and A represents a chalcogen of an atomic weight of 16 to 32.

8. The compound, 2-cyano - 1 - (2-hydroxyethyl)-5-(2-hydroxyethylimino)-2,4,4-trimethylpyrrolidine.

9. The compound, 2-cyano - 5 - dodecylimino-2,4,4-trimethylpyrrolidine.

10. The compound, 2-cyano - 1 - dodecyl-5-imino-2,4,4-trimethylpyrrolidine.

11. The compound, 2-aminomethyl - 5 - dodecylimino-2,4,4-trimethylpyrrolidine.

12. The compound, 5-benzylimino - 2 - hydroxy-2,4,4-trimethylpyrrolidine.

13. A method for the preparation of the compound

60

65

70

75

having the formula

which comprises reacting

5 with hydrocyanic acid in the temperature range of about 0° to 325° C. in which the hydrocyanic acid is added at a rate substantially equal to the rate of reaction, in which the symbols R, R², R³, R⁴, and R⁵ have the same significance as in claim 16, R¹ is an alkyl group of 1 to 10 carbon atoms, and R⁸ is a member selected from the class consisting of an alkyl group of 1 to 9 carbon atoms and a hydrogen atom.

10 14. A method for the preparation of a compound having the formula

25 30 which comprises reacting in substantially equimolecular proportions in the temperature range of about 0° to 70° C., the compound having the formula R⁶NH₂ with the compound having the formula

35 40 45 in which the symbols R, R², R³, R⁴, and R⁵ have the same significance as in claim 18, R¹ is an alkyl group of 1 to 10 carbon atoms, R⁶ represents an alkyl group of 1 to 18 carbon atoms, and R⁸ is a member selected from the class consisting of an alkyl group of 1 to 9 carbon atoms and a hydrogen atom.

15 45 50 55 15. A method for the preparation of the compound having the formula

which comprises reacting

60 65 70 75 with R⁷AH in the temperature range of about 20° to about 75° C., in which the symbols R, R², R³, R⁴, and R⁵ have the same significance as in claim 19, R¹ is an alkyl group of 1 to 10 carbon atoms, and R⁸ is a member selected from the class consisting of an alkyl group of 1 to 9 carbon atoms and a hydrogen atom.

16. A method for the preparation of the compound having the formula

in which R and R⁵ are each members selected from the class consisting of hydrogen, alkyl groups of 1 to 18 carbon atoms, phenyl, naphthyl, phenylalkyl groups of up to 18 carbon atoms, alkylphenylalkyl groups of up to 30 carbon atoms, alkoxyalkyl groups of 3 to 24 carbon atoms, hydroxyalkyl groups of 2 to 12 carbon atoms, and alkylaminoalkyl groups of 3 to 18 carbon atoms, R¹ taken individually represents a member selected from the class consisting of alkyl, phenylalkyl, cycloalkyl, phenyl, naphthyl, and alkylphenyl groups of no more than 10 carbon atoms, R² taken individually represents a member selected from the class consisting of hydrogen and alkyl groups of 1 to 4 carbon atoms, R³ and R⁴ taken individually represent members selected from the class consisting of hydrogen, alkyl, cycloalkyl, phenylalkyl, phenyl, naphthyl, and alkylphenyl groups of up to 10 carbon atoms, R¹ and R² taken collectively with the carbon atoms to which they are joined form a carbocyclic ring of 5 to 6 carbon atoms free of aromatic unsaturation including alkyl substituents of a total of no more than 4 additional carbon atoms, R² and R³ taken collectively with the carbon atoms to which they are joined form a carbocyclic ring of 5 to 6 carbon atoms free of aromatic unsaturation including alkyl substituents of a total of no more than 4 additional carbon atoms, R³ and R⁴ taken collectively with the carbon atoms to which they are joined form a carbocyclic ring of 5 to 6 carbon atoms free of aromatic unsaturation including alkyl substituents of a total of no more than 4 additional carbon atoms, which comprises reacting a compound whose principal tautomeric form is represented by the formula

with hydrocyanic acid in the temperature range of 0° to 325° C. in which the hydrocyanic acid is added at a rate substantially equal to the rate of reaction.

17. A method for the preparation of the compound having the formula

which comprises reacting substantially one equivalent of the compound having the formula

with hydrogen in the temperature of 75° to 250° C. in the presence of a hydrogenation catalyst, in which R and R⁵ are each members selected from the class consisting of hydrogen, alkyl groups of 1 to 18 carbon atoms, phenyl, naphthyl, phenylalkyl groups of up to 18 carbon atoms, alkylphenylalkyl groups of up to 30 carbon atoms, alkoxyalkyl groups of 3 to 24 carbon atoms, hydroxyalkyl groups of 2 to 12 carbon atoms, and alkylaminoalkyl groups of 3 to 18 carbon atoms, R¹ taken individually represents a member selected from the class consisting of alkyl, phenylalkyl, cycloalkyl, phenyl, naphthyl, and alkylphenyl groups of no more than 10 carbon atoms, R² taken individually represents a member selected from the class consisting of hydrogen and alkyl groups of 1 to 4 carbon atoms, R³ and R⁴ taken individually represent members selected from the class consisting of hydrogen, alkyl, cycloalkyl, phenylalkyl, phenyl, naphthyl, and alkylphenyl groups of up to 10 carbon atoms, R¹ and R² taken collectively with the carbon atoms to which they are joined form a carbocyclic ring of 5 to 6 carbon atoms free of aromatic unsaturation including alkyl substituents of a total of no more than 4 additional carbon atoms, R² and R³ taken collectively with the carbon atoms to which they are joined form a carbocyclic ring of 5 to 6 carbon atoms free of aromatic unsaturation including alkyl substituents of a total of no more than 4 additional carbon atoms, R³ and R⁴ taken collectively with the carbon atoms to which they are joined form a carbocyclic ring of 5 to 6 carbon atoms free of aromatic unsaturation including alkyl substituents of a total of no more than 4 additional carbon atoms, which comprises reacting a compound whose principal tautomeric form is represented by the formula

saturation including alkyl substituents of a total of no more than 4 additional carbon atoms, R² and R³ taken collectively with the carbon atoms to which they are joined form a carbocyclic ring of 5 to 6 carbon atoms free of aromatic unsaturation including alkyl substituents of a total of no more than 4 additional carbon atoms, and R³ and R⁴ taken collectively with the carbon atoms to which they are joined form a carbocyclic ring of 5 to 6 carbon atoms free of aromatic unsaturation including alkyl substituents of a total of no more than 4 additional carbon atoms.

18. A method for the preparation of the compound having the formula

which comprises reacting in substantially equimolecular proportions in the temperature range of about 0° to 70° C., the compound having the formula R⁶NH₂ with one whose principal tautomeric form is represented by the formula

in which R and R⁵ are each members selected from the class consisting of hydrogen, alkyl groups of 1 to 18 carbon atoms, phenyl, naphthyl, phenylalkyl groups of up to 18 carbon atoms, alkylphenylalkyl groups of up to 30 carbon atoms, alkoxyalkyl groups of 3 to 24 carbon atoms, hydroxyalkyl groups of 2 to 12 carbon atoms, and alkylaminoalkyl groups of 3 to 18 carbon atoms, R¹ taken individually represents a member selected from the class consisting of alkyl, phenylalkyl, cycloalkyl, phenyl, naphthyl, and alkylphenyl groups of no more than 10 carbon atoms, R² taken individually represents a member selected from the class consisting of hydrogen and alkyl groups of 1 to 4 carbon atoms, R³ and R⁴ taken individually represent members selected from the class consisting of hydrogen, alkyl, cycloalkyl, phenylalkyl, phenyl, naphthyl, and alkylphenyl groups of up to 10 carbon atoms, R¹ and R² taken collectively with the carbon atoms to which they are joined form a carbocyclic ring of 5 to 6 carbon atoms free of aromatic unsaturation including alkyl substituents of a total of no more than 4 additional carbon atoms, R² and R³ taken collectively with the carbon atoms to which they are joined form a carbocyclic ring of 5 to 6 carbon atoms free of aromatic unsaturation including alkyl substituents of a total of no more than 4 additional carbon atoms, R³ and R⁴ taken collectively with the carbon atoms to which they are joined form a carbocyclic ring of 5 to 6 carbon atoms free of aromatic unsaturation including alkyl substituents of a total of no more than 4 additional carbon atoms, R⁵ and R⁶ taken collectively with the carbon atoms to which they are joined form a carbocyclic ring of 5 to 6 carbon atoms free of aromatic unsaturation including alkyl substituents of a total of no more than 4 additional carbon atoms, R² and R³ taken collectively with the carbon atoms to which they are joined form a carbocyclic ring of 5 to 6 carbon atoms free of aromatic unsaturation including alkyl substituents of a total of no more than 4 additional carbon atoms, R³ and R⁴ taken collectively with the carbon atoms to which they are joined form a carbocyclic ring of 5 to 6 carbon atoms free of aromatic unsaturation including alkyl substituents of a total of no more than 4 additional carbon atoms, R⁵ and R⁶ taken collectively with the carbon atoms to which they are joined form a carbocyclic ring of 5 to 6 carbon atoms free of aromatic unsaturation including alkyl substituents of a total of no more than 4 additional carbon atoms, which comprises reacting a compound whose principal tautomeric form is represented by the formula

which comprises reacting the compound whose principal

21

tautomeric form has the formula

with one having the formula R^7AH in which the AH group is attached to a member selected from the class consisting of a hydrogen atom and a carbon atom that is in turn attached to no more than two other carbon atoms from the group R^7 at a temperature of about 20° to about 75° C. and in which R and R^5 are each members selected from the class consisting of hydrogen, alkyl groups of 1 to 18 carbon atoms, phenyl, naphthyl, phenylalkyl groups of up to 18 carbon atoms, alkylphenylalkyl groups of up to 30 carbon atoms, alkoxyalkyl groups of 3 to 24 carbon atoms, hydroxyalkyl groups of 2 to 12 carbon atoms, and alkylaminoalkyl groups of 3 to 18 carbon atoms, R^1 taken individually represents a member selected from the class consisting of alkyl, phenylalkyl, cycloalkyl, phenyl, naphthyl, and alkylphenyl groups of no more than 10 carbon atoms, R^2 taken individually represents a member selected from the class consisting of hydrogen and alkyl groups of 1 to 4 carbon atoms, R^3 and R^4 taken individually represent members selected from the class consisting of hy-

22

drogen, alkyl, cycloalkyl, phenylalkyl, phenyl, naphthyl, and alkylphenyl groups of up to 10 carbon atoms, R^1 and R^2 taken collectively with the carbon atoms to which they are joined form a carbocyclic ring of 5 to 6 carbon atoms free of aromatic unsaturation including alkyl substituents of a total of no more than 4 additional carbon atoms, R^2 and R^3 taken collectively with the carbon atoms to which they are joined form a carbocyclic ring of 5 to 6 carbon atoms free of aromatic unsaturation including alkyl substituents of a total of no more than 4 additional carbon atoms, R^3 and R^4 taken collectively with the carbon atoms to which they are joined form a carbocyclic ring of 5 to 6 carbon atoms free of aromatic unsaturation including alkyl substituents of a total of no more than 4 additional carbon atoms, R^7 is a member selected from the class consisting of a hydrogen atom, an alkyl group of 1 to 12 carbon atoms, an alkenyl group of 3 to 12 carbon atoms, phenyl, naphthyl, a phenylalkyl group of up to 12 carbon atoms, an alkylphenylalkyl group of up to 12 carbon atoms, an alkoxyalkyl group of 3 to 12 carbon atoms, a hydroxyalkyl group of up to 12 carbon atoms, and an alkylaminoalkyl group of 3 to 18 carbon atoms, and A is a chalcogen of an atomic weight of 16 to 32.
